DISPLAY SUPPORT

Murray Zlotziver, Los Angeles, Calif.

Application February 2, 1937, Serial No. 123,575

7 Claims. (Cl. 211—71)

This invention relates to display supports.

The general object of the invention is to provide an improved display support particularly adaptable for use in supporting meat dealers' trays.

5 A more specific object of the invention is to provide a tray support for use in connection with refrigerator units wherein novel means is provided for holding the trays elevated or inclined in display position.

10 Another object of the invention is to provide a rack having means thereon for holding trays elevated or inclined.

15 Other objects and the advantages of my invention will be apparent from the following description taken in connection with the accompanying drawing, wherein:

20 Fig. 1 is a top plan view of a display support embodying the features of my invention;

Fig. 2 is a section taken on line 2—2 Fig. 1;

25 Fig. 3 is a section taken on line 3—3 Fig. 1; and

Fig. 4 is a fragmentary section through a display case showing my display support used therein.

25 Referring to the drawing by reference characters I have shown my invention as embodied in a display support which is indicated generally at 9. As shown this support includes a frame member comprising side portions 10, a front portion 11 and a rear 12. The frame is preferably made of a heavy wire or rod. Transverse members 13 extend from one side of the frame to the other and are preferably welded to the frame as at 14.

30 At the front, short longitudinally extending rods 15 extend from the portion 11 to the adjacent cross member 13. Three of these rods at the center, and which are indicated at 16, extend the full length of the frame and are welded or otherwise secured to the rear portion 12 and to the cross members 13.

35 Arranged between the cross members 13 I show base supports 17. These supports 17 have teeth 18 which are upwardly directed. These base supports are shown as arranged in pairs and their teeth are engaged by U-shaped arms 19 which are pivoted in lugs 20 on U-shaped supports 21. The U-shaped supports 21 are arranged between the rods 16 and the sides 10, and are pivoted as by bending at 21' to the cross members 13 as shown in Fig. 2 of the drawing. The U-shaped supports 21 are of such a length that they extend from one cross member to a location near the rear of the adjacent cross member.

The length of the arms 19 is such that these arms fit in the rear tooth when they are in the position shown at the left in Fig. 2 thus disposing them beneath the top of the cross members 16 and allowing the support 21 to lie flush with the top of the members 15 and 16 as shown in Fig. 2 when all parts are collapsed.

5 My meat display support is particularly adapted for use in supporting meat holding trays in refrigerator cases in meat markets, although it 10 may be used for other purposes.

In Fig. 4 of the drawing I show my invention as used with a meat display case 22 which includes a transparent front 23, and a transparent top panel 24 with a hinged door 25 allowing access 15 to the case. The case is provided with supports 26 which are in the nature of upwardly directed hooks and which engage the frame 10. After the frame is positioned, the supports 21 are moved to the desired inclination and the trays are arranged thereon.

20 In Fig. 4 the front tray 27 is inclined more sharply and engages the front panel 23 as shown. The rear tray 28 is arranged at an angle so that the contents of both trays 27 and 28 can be readily 25 viewed through the panels 23 and 24 and the housewife can make her selection without difficulty.

From the foregoing description it will be apparent that I have invented a novel display support which can be economically manufactured and which is highly efficient in use.

30 Having thus described my invention, I claim:

1. In a display support, a frame, cross members extending from one side of the frame to the other, a plurality of supports pivoted on said cross members, said supports being U-shaped and extending rearwardly from the cross member on which they are pivoted and terminating in advance of the next rearward cross member, a 35 U-shaped arm pivoted on each of said U-shaped supports, a pair of base supports secured to the cross members beneath each of said U-shaped supports, said base supports having upwardly directed teeth thereon adapted for engagement with the U-shaped arms.

2. In a display support, a rectangular frame including a front portion, a rear portion and spaced side portions, cross members extending from one side of the frame to the other, rods 40 spaced apart and extending from said front member to the adjacent cross member, other rods extending from said front member to said rear member adjacent to the middle of said frame, a plurality of supports pivotally engaging 45

the members, said supports being U-shaped and extending rearwardly from the cross member on which they are pivoted, an arm pivoted on each of said U-shaped supports, a base support secured to the frame and arranged beneath each of said U-shaped supports, said base supports having upwardly directed teeth thereon adapted for engagement with the pivoted arms.

5. In a display support, a rectangular frame including a front portion, a rear portion and spaced side portions, cross members extending from one side of the frame to the other, a plurality of rods spaced apart and extending from said front member to the adjacent cross member,

10 other rods extending from said front member to said rear member adjacent to the middle of said frame, a plurality of supports pivoted on said cross members, said supports having loops at the front ends engaging a cross member, said supports being U-shaped and extending rearwardly from the cross member on which they are pivoted and terminating in advance of the next rearward cross member, a U-shaped arm pivoted on each of said U-shaped supports,

15 20 25 30 35 40 45

25 a pair of base supports secured to the cross members beneath each of said U-shaped supports, said base supports having upwardly directed teeth thereon adapted for engagement with the U-shaped arms.

30 4. In a display support, a rectangular frame including a front portion, a rear portion and spaced side portions, cross members extending from one side of the frame to the other, said cross members and said frame being made of wire and arranged with their tops and bottoms flush with each other, a plurality of supports, said supports comprising metal members each having loops at the front ends engaging a cross member, said supports being U-shaped and extending rearwardly from the cross member on which they are pivoted and terminating in advance of the next rearward cross member, a U-shaped arm pivoted on each of said U-shaped supports, a pair of base supports secured to the cross members beneath each of said U-shaped supports, said base supports having upwardly directed teeth thereon adapted for engagement with the U-shaped arms.

40 45 50 55 55

5. In a display support, a rectangular frame including a front portion, a rear portion and spaced side portions, cross members extending from one side of the frame to the other, said cross members and said frame being made of wire and arranged with their tops and bottoms flush with each other, a plurality of rods spaced apart and extending from said front member to the adjacent cross member, other rods extending from said front member to said rear member

adjacent to the middle of said frame, said last mentioned rods being secured to the front and rear members and to the cross members, a plurality of tray supports comprising flat metal bars having loops at the front ends engaging a cross member, said supports extending rearwardly from the cross member on which they are pivoted and terminating in advance of the next rearward cross member, an arm pivoted on each of said tray supports, a base support secured to the cross members beneath each of said tray supports, said base supports having upwardly directed teeth thereon adapted for engagement with an arm.

6. In a display support, a rectangular frame including a front portion, a rear portion and spaced side portions, cross members extending from one side of the frame to the other, said cross members and said frame being made of wire and arranged with their tops and bottoms flush with each other, a plurality of rods spaced apart and extending from said front member to the adjacent cross member, other rods extending from said front member to said rear member adjacent to the middle of said frame, said last mentioned rods being secured to the front and rear members and to the cross members, a plurality of supports, said supports comprising flat metal bars having loops at the front ends engaging a cross member, said supports being U-shaped and extending rearwardly from the cross member on which they are pivoted and terminating in advance of the next rearward cross member, a U-shaped arm pivoted on each of said U-shaped supports, a pair of base supports secured to the cross members beneath each of said U-shaped supports, said base supports having upwardly directed teeth thereon adapted for engagement with the U-shaped arms.

7. In a display support, a rectangular frame including a front portion, a rear portion and spaced side portions, cross members secured to the side portions and extending from one side of the frame to the other side thereof, rods secured to the frame and spaced apart and extending longitudinally of the frame and parallel to the side portions, a plurality of supports pivotally engaging the cross members and arranged between the cross members, said supports being U-shaped and extending rearwardly from the cross member on which they are pivoted, a supporting arm pivoted on each of said U-shaped supports, a base support arranged beneath each of said U-shaped supports and secured to the frame, said base supports having upwardly directed engaging portions thereon adapted for engagement with the pivoted arms.

MURRAY ZLOTZIVER.
